UNITED STATES PATENT OFFICE.

SANG M. HO, OF NEW YORK, N. Y., ASSIGNOR TO MAY CHONG CO. INC., OF NEW YORK, N. Y.

DESIGN FOR A TEXTILE FABRIC.

Application filed November 27, 1925. Serial No. 15,560. Term of patent 3½ years.

To all whom it may concern:

Be it known that I, SANG M. Ho, a citizen of the United States of America, residing at New York, in the county of New York and State of New York, have invented a new, original, and ornamental Design for Textile Fabrics, of which the following is a specification, reference being had to the accompanying drawing, forming part thereof.

The figure is a fragmentary elevation of a piece of fabric embodying the new design.

I claim:

The ornamental design for textile fabric as shown.
